UNITED STATES PATENT OFFICE

168,549

INITIALED SPECTACLE FRONT

Samu-El Ish-Shalom, New York, N. Y.

Application July 30, 1952, Serial No. 20,851

Term of patent 14 years

(Cl. D57—1)

To all whom it may concern:

Be it known that I, Samu-El Ish-Shalom, a citizen of the United States of America, residing at New York, N. Y., have invented a new original, and ornamental Design for an Initialed Spectacle Front, of which the following is a specification, reference being had to the accompanying drawing, forming part hereof.

The dominant features of the design reside in the portions shown in full lines.

I claim:

The ornamental design for an initialed spectacle front, as shown and described.

SAMU-EL ISH-SHALOM.
